SAFETY DEVICE FOR BLASTING CABLES

Thomas C. Luke and Albert Mariotti, McComas,
W. Va., assignors of one-fourth to Carl Mariotti

Application May 23, 1939, Serial No. 275,308

1 Claim. (Cl. 200—168)

This invention relates to a safety device for use in connection with a cable used from a battery to a detonator or blasting cap as in mines, which require that the wires of the cable be normally shunted or short-circuited.

It is especially aimed to provide a construction in which the shunting or short-circuiting is effected within a rubber or other pliable element adapted for compression to separate the contacts or conductors when a circuit is to pass therethrough.

It is also aimed to provide such a structure with one dimension preferably greater than the other, so that when the device rests upon the ground and is accidentally tread upon, the contacts will be brought into more effective shunting or short-circuiting engagement, rather than being opened or separated.

The more specific objects and advantages will become apparent from a consideration of the description following taken in connection with the accompanying drawing illustrating an operative embodiment.

In said drawing:

Figure 1 is a view in side elevation showing our improvements applied to a cable;

Figure 2 is a view taken at a right angle to Figure 1;

Figure 3 is a plan view;

Figure 4 is a vertical section taken on the line 4—4 of Figure 3;

Figure 5 is a view taken through the device at a right angle to Figure 4; with one of the block sections removed;

Figure 6 is a cross sectional view taken on the plane of line 6—6 of Figure 1, and

Figure 7 is a view similar to Figure 5 but presuming flattening or compression of the blocks to separate the contacts.

Referring specifically to the drawing wherein like reference characters designate like or similar parts, 10 represents conductors as used to provide an electric circuit from a battery (not shown) to a blasting cap or detonator as used in a mine. Normally, the wires 10 for safe purposes, are required to be shunted or short-circuited by contact with each other, to prevent danger of accidental or premature blasting. When the wires are directly joined or twisted together, they soon lose their effectiveness by crystallization and the like.

According to the present invention, portions of each wire have the insulation 11 removed therefrom as at 12 and are secured within contacts 13 generally of H-shape as best shown in Figure

6. Such contacts consist of a single strip of metal bent to form a double flange at 14 at opposite sides thereof, terminal flanges 15 at opposite sides therefrom, and webs 16 connecting the flanges 15 and 14. The webs 16 may be soldered together and portions 12 soldered to the adjacent portions of the contacts to effect better connections.

Said contacts have enlargements or wings at 17 which are normally in engagement to shunt 10 or short-circuit the conductors 10.

Said contacts are suitably embedded in a manually compressible body 18 usually consisting of sections 19 of pliable rubber or other insulation which are cemented or joined together at a junction plane 20. It will be noted that the flanges 15 occupy recesses or spaces 21 in the sections 19 while the flanges 14 occupy a central recess or space 22 of the blocks. To insure sufficient spread of the contacts 17 to prevent short-circuiting the detonator circuit the body portion 18 is provided with recessed portions 23 communicating with recess or space 22.

As stated, the circuit will normally be shunted or short-circuited since the contacts are in engagement at the flanges 17 and are urged into and maintained in such engagement through the contractile action of the rubber sections 19. However, at the time an electric circuit is to be passed through the conductors 12 to fire a detonator or blasting cap, the body 18 is compressed at its greater transverse dimension as at the points and in the directions indicated by the arrows in Figure 6. Such action causes the rubber body 18 to bulge at a right angle to the line of compression, thereby separating the contact portions 17 and hence an electric circuit may readily be closed through the conductors from the battery to the detonator or blasting cap. However, upon release of the elastic body, it will assume its normal position, shown in the drawing, again shunting or short-circuiting the wires 10.

Attention is called to the fact that if the structure should rest on the ground, and be tread upon, such treading would tend to establish more firm contact between the portions 17, since the body would fall and rest on its wider rather than narrower dimension.

Various changes may be resorted to provided they fall within the spirit and scope of the invention.

We claim as our invention:

A device of the class described having a resilient body, conductor means passing through the body, said conductor means having portions nor- 55

5 mally maintained in contact by the resilience of said body to provide a short circuit and adapted for separation through compression of the body to enable closing of a circuit through the conductor means, said conductors including contacts arranged for engagement at portions thereof, the body having recesses and the conductors having flanges spaced outwardly from said portions extending into adjacent recesses whereby the con-

tacts are anchored to the body to move with and through the compression of the latter, said contacts being in a single strip and enclosing a portion of the conductors and generally being of H-shape to provide inner and outer flanges, the body having a recess, the inner flanges of both contacts being located within said recess. 5
